UNITED STATES PATENT OFFICE.

BRADY MURPHY PERDUE, OF FRANKLIN, KENTUCKY.

BUGGY-SHAFT SUPPORT.

1,112,929.

Specification of Letters Patent.

Patented Oct. 6, 1914.

Application filed July 11, 1913. Serial No. 778,556.

To all whom it may concern:

Be it known that I, BRADY MURPHY PERDUE, a citizen of the United States, and a resident of Franklin, in the county of Simpson and State of Kentucky, have invented an Improvement in Buggy-Shaft Supports, of which the following is a specification.

My invention is an improvement in that class of devices which are applied to horse-drawn vehicles for the purpose of supporting the shafts in elevated position when the vehicle is not in use.

The invention is more particularly an improvement upon that for which I have received Letters Patent of the United States, No. 1,050,687, dated January 14, 1913. In the former invention, a shaft-engaging and supporting hook is pivoted to a vertical bracket or standard in such manner that a portion of it projects backward from the standard, and is acted on by a spiral spring which is applied to the standard exteriorly. In the present invention the spring is inclosed in a hollow standard and engages the hook on the front side of its pivot.

In the accompanying drawing Figure 1 is a vertical section of a portion of a vehicle front with my invention applied and the hook shown supporting the shafts. Fig. 2 is a vertical section of the hollow standard with the hook and spring applied and the former in the pendent position or disengaged from the shafts.

A hollow standard 1 is rigidly attached to

the front spring of a vehicle, and a hook 2 is pivoted in the slotted end of the same. A contractile spiral spring 3 is arranged in the adjacent portion of the standard and its lower end is secured to the latter, while the upper end is attached to the hook in front of its pivot. As shown, the hook is pendent from the standard and is adapted to engage the cross-bar 5 of the shafts 4, when the latter are elevated at the required angle, as shown in Fig. 1. It will be understood that in order to effect such engagement, the shafts are elevated until the cross-bar 5 passes over the nose of the hook, and then upon lowering the shafts and pulling the hook forward it is brought under the cross-bar and the weight of the shaft then presses upon the hook and holds the parts engaged. This arrangement and attachment of the hook is preferable to the former one, since the spring is inclosed and protected and prevented from contact with exterior objects.

I claim:

The combination with a vehicle and shafts hinged thereto and a hollow standard rigidly secured to the front of the vehicle, of a hook pivoted in the standard, and a spiral spring inclosed in the latter and engaging the hook in front of its pivot, as described.

BRADY MURPHY PERDUE.
